ors to The Linde Air Products Company, a cor-
poration of Ohio

Application November 11, 1943, Serial No. 509,840

11 Claims. (Cl. 123—174)

1

This invention relates to a new and improved liquid circulation system for cooling internal combustion engines, and more specifically it concerns an improved cooling system for airplane motors having a remarkable degree of over-all cooling efficiency at high altitudes.

It is a recognized fact that modern liquid cooling aircraft engines are difficult to cool efficiently when operating under high altitude conditions. This is due in part to a reduction in density of the cooling air with increasing altitudes, but it may be due even in larger part to the failure of the usual cooling systems to maintain continually full circulation of the cooling fluid at all altitudes. Vapor binding, or cavitation, in the coolant pump, caused by boiling of the coolant at or near the pump intake, can readily occur under high solution temperatures and low atmospheric pressure, and this in turn can result in a substantial decrease in coolant flow, with serious loss in cooling efficiency. These difficulties are exaggerated when the cooling system is not sealed to the atmosphere, and when, as is usually the case, the pressure at the inlet to the pump, or actually at the hub of the impeller, is lower than at any other point in the circulation system.

A remedy heretofore proposed for this problem comprises the use of a pressure actuated valve on the expansion tank of the cooling system, which otherwise is air-tight, and consists of the conventional parts, including the engine block, radiator and pump. The expansion tank serves the normal purposes of a reservoir for excess coolant during warming of the engine, and a settling chamber for removal of air or vapor from the cooling liquid. With a pressure cap on this tank, thermal expansion and vaporization of the coolant are relied on to increase and control the internal pressure in the entire system, but while the latter result is accomplished, the relative pressures throughout the system are not changed, and the minimum pressure point in the circulation line still remains ordinarily at the pump inlet. Hence boiling of the coolant again tends to occur first at this location, which reduces the pump effectiveness before a corrective pressurizing due to boiling in the expansion tank can actually take place. Difficulty is also encountered in proper venting of the pressure valve in this arrangement, which in release position usually allows the pressure in the expansion tank to be lowered almost to that of the outside atmosphere, and this again destroys the desired pressure control in the system. Other troubles

arise with the use of high boiling coolants which will not normally vaporize sufficiently to increase substantially the pressure on the expansion tank liquid. The system as described is, therefore, unsatisfactory, and is unreliable in preventing pump cavitation at the higher altitudes.

In another embodiment proposed in the prior art, a Venturi tube is incorporated in the circulation line at a point just before the pump, and a conventional expansion tank is connected to the throat of a venturi. The venturi functions in usual manner, and creates a zone of low static pressure in the constricted throat, at which point the head pressure of liquid in the expansion tank is impressed, thus increasing the pressure at the pump intake and throughout the entire system. This design is an improvement over the modification employing only a pressure valve on the expansion tank, but through the fault of allowing the customary coolant flow through the part of the system including the expansion tank and its Venturi connection, only a partial pressurizing effect is accomplished. This flow of the coolant into the Venturi throat disturbs the normal, and desired, action of the venturi, and it furthermore causes a substantial drop in the head pressure exerted at this point. The ultimate result is that the lowest pressure in such a system is at the Venturi throat and the system has definite altitude limitations so far as satisfactory performance is concerned.

It is an object of our invention to provide a circulatory cooling system for internal combustion engines which is adapted to operate under any atmospheric conditions with an efficient and full circulation of required volumes of coolant.

A further object is to provide a cooling system for airplane engines, wherein vapor binding at the circulating pump, and pump cavitation, are virtually eliminated at all altitudes.

Another object is to provide an engine cooling system in which deaeration of the coolant is effected, in combination with the maintenance of an internal pressure control which prevents pump cavitation.

The objects stated, and other advantages, are achieved essentially by a modification wherein means are provided to maintain consistently a minimum pressure point in the system which is at a position outside, or removed from, the main coolant circuit. This is accomplished through an arrangement in which a coolant reservoir, herein designated as a static reserve tank, is associated with the cooling system, which in other respects can be substantially of conventional design, and

may include a second coolant reservoir serving at least one of the usual purposes of an expansion tank. There is no coolant flow through the static reserve tank, or in any event no more than a very small flow of liquid, and this tank is connected with the main circulation line at, or near, the point where lowest pressure in the system usually occurs. The latter point is normally in the vicinity of the propeller eye of the pump, but for convenience, and to alleviate mechanical difficulties in making an attachment at this position, a low pressure point can be created outside the pump by means of a Venturi tube or similar device. Thus the liquid head pressure of the coolant in the static tank and connecting leg is impressed on the system, which raises the pump pressure accordingly, and causes the minimum pressure point in the system to be transferred to, and remain in, the static tank. Suitable vapor venting means on the static tank aid in maintaining the pressure control indicated, and permit an over-all pressurizing effect on the system which is not substantially greater than that required to obtain continuously a full circulation of coolant. With additional means for holding the temperature of the coolant in the static tank higher than it is in the pump, boiling will not occur at, or near, the pump; and pump cavitation and vapor binding is prevented under all altitude conditions.

The accompanying drawing will be further descriptive of the invention, and shows diagrammatically a cooling system embodiment which will produce results as alleged.

In the drawing a primary circulating system is indicated for the engine block 10 as including connective pipe 12, radiator 14, connective pipe 16, pump 18 and connective pipe 20. This primary circulating system according to our invention will also preferably include the Venturi tube 22, as shown just before the pump in connective pipe 16. The secondary, circulating system, through which there is only a partial coolant circulation, includes connective pipe 24, leading from engine block 10 to an expansion tank 28, and the return pipe 27 connecting the expansion tank to the inlet of the pump.

Within the expansion tank 28 there is a second tank 30, which constitutes a static coolant reserve tank as previously described. The tank 28 is preferably designed as a centrifuge, in order to deaerate continually the coolant, and since it completely surrounds the tank 30, the coolant in both tanks is kept at approximately the same temperature. The two tanks are connected by means of a pipe 32 of small diameter, the latter being provided with a needle valve 34 which can be closed by the projection 35 on top of the valve float 36. Valve 34 will normally be held in the closed position because of the buoyant effect of the liquid in tank 28, but will open to allow exit of air from tank 28 as entrained air is discharged and collects at the top portion of this centrifuge tank. Pipe 32, and associated parts, will readily permit flow of air or vapor, but the needle valve 34 prevents substantial liquid flow between the tanks.

The pipe 38, with cap 40, provides a filler port for the system, and carries a bleeder pipe 42, which connects with the float chamber extension on tank 28. This bleeder pipe 42 is for the purpose of venting air during the initial filling, so that complete distribution of the coolant occurs throughout the system. The static coolant reserve tank 30 is provided with a vent pipe 46,

5 which carries a safety valve 48, and leads to an outboard vent 50 through an adjustable diaphragm pressure release valve 52. The latter valve can be adjusted to control and hold a pressure which will prevent free boiling and excessive loss of vapor from tank 30, and with the aid of a small orifice plate 51 just ahead of the valve 52, venting of this valve can take place without allowing the system to equalize in pressure with the outside atmosphere.

10 A connection pipe 54 joins the static tank 30 to the throat of the venturi 22, but since the system is completely closed and the main circulation line is entirely filled with coolant liquid, there is very little, if any, coolant flow into the Venturi throat from the static tank. Thus the static liquid head pressure of the coolant in tank 30 and its connecting leg is impressed at the point of lowest pressure in the system, and in accordance with the well-known hydraulic laws of Bernoulli, a corresponding pressure boost occurs in the pump, and the pump intake pressure always exceeds the pressure in the static tank by an amount approximately that of the static liquid head at the Venturi throat. The coolant in centrifugal tank 28, being taken directly from the engine block, keeps the static tank coolant at a higher temperature than the fluid entering the pump from the radiator, and this provides further assurance that boiling in the static tank will always occur before the coolant flowing to the pump reaches boiling temperature. Hence a self-balancing pressurizing effect is attained, regardless of altitude conditions, and full pump circulation rate continues under all normal engine operating conditions.

15 It will be understood that many modifications over the system specifically described are possible, utilizing the essential features of the invention. As previously indicated a similar static tank assembly can be used without the venturi to produce good results, in which case the connective leg of this tank is joined to the system directly at the pump intake, or at another position where minimum pressure exists. In place of the Venturi tube, an ordinary orifice, Pitot tube, or similar device may be used to create a suitable low pressure zone before the pump. Maintenance of a suitable temperature in the static tank liquid can be conveniently accomplished as shown, but a heat exchange arrangement with the hot engine exhaust gases, or a surrounding rheostat-controlled electric heater, are other ways of attaining the same end, and may be equally suitable. 20 With a modified heating means for the static tank, the latter may be entirely separate from the expansion tank assembly, without a venting means between the two tanks; in which case there need be no flow of fluid whatever through the static reserve tank. It is not essential that the expansion tank be of centrifuge structure, as one of more conventional type may be satisfactory, where continual deaeration of the coolant is not necessary or desired, and in the latter situation the static tank itself might be made to serve the additional function of the usual expansion tank as a reservoir for excess coolant. Many embodiments in the way of valves and venting means on both the expansion tank and the static tank may also be appropriate to maintain the required pressure control in the system, and the relative positions and dimensions of the respective parts illustrated can be varied to adapt the invention to different engine assemblies.

25 The above and other modifications will be ob-

vious to those skilled in the art, and are intended to be included within the broader scope of the invention as defined in the appended claims.

We claim:

1. In a liquid cooling system for internal combustion engines having a primary circulation line including the engine block, a radiator and coolant pump, the combination of a coolant reservoir through which no substantial fluid flow occurs, a connection from said reservoir to a point of normal low pressure in said primary circulation line, whereby head pressure of the reservoir coolant is impressed on the system, and means maintaining the temperature of said reservoir coolant higher than the temperature of the coolant in the circulation line at said connection point.

2. A system as defined in claim 1, in which the specified temperature of the reservoir coolant is maintained by heat exchange relation with hot effluent coolant from the engine block.

3. A system as defined in claim 1, in which the point of low pressure in the primary circulation line is created by a static pressure reducing device connected before the pump intake.

4. A system as defined in claim 1, which additionally includes a pressure venting means on said coolant reservoir adapted to control the vapor pressure therein.

5. A liquid cooling system for internal combustion engines comprising a primary circulation line including the engine block, a radiator and a coolant pump; an expansion tank connected to permit at least partial circulation of effluent engine block coolant; a static coolant reserve tank positioned in heat exchange relationship with the expansion tank coolant; a connection from said static tank to a point of normal minimum pressure in the primary circulation line, through which head pressure of the static tank coolant is impressed on the system; and pressure venting means on said static coolant reserve tank to control the vapor pressure therein.

6. A liquid cooling system for internal combustion engines comprising a primary circulation line including the engine block, a radiator and a coolant pump; an expansion tank connected to permit at least partial circulation of effluent engine block coolant; a static coolant reserve tank within said expansion tank and in heat exchange relationship with the coolant therein; a connection from said static tank to the pump intake, through which liquid head pressure of the static tank coolant is impressed on the system; and pressure venting means on said static coolant reserve tank to control the vapor pressure therein.

7. A liquid cooling system as defined in claim 6, in which said expansion tank is of a centrifuge structure adapted to deaerate the coolant circulating therethrough.

8. A liquid cooling system for internal combustion engines comprising a primary circulation line including the engine block, a radiator, a coolant

pump, and a venturi before the intake to said pump; an expansion tank connected to permit at least partial circulation of effluent engine block coolant; a static coolant reserve tank within said expansion tank and in heat exchange relationship with the coolant therein; a connection from said static tank to the throat of said venturi through which liquid head pressure of the static tank coolant is impressed on the system; and pressure venting means on said static coolant reserve tank to control the vapor pressure therein.

9. A liquid cooling system for internal combustion engines comprising a primary circulation line including the engine block, a radiator, a coolant pump, and a venturi before the intake to said pump; an expansion tank connected to permit at least partial circulation of effluent engine block coolant; a static coolant reserve tank within said expansion tank and in heat exchange relationship with the coolant therein; a connection from said static tank to the throat of said venturi through which liquid head pressure of the static tank coolant is impressed on the system; a connection between said expansion tank and said static coolant reserve tank adapted readily to permit venting of air and vapor from the former to the latter tank and to resist similar flow of liquid; and pressure venting means on said static coolant reserve tank to control the vapor pressure therein while preventing an equalization of pressure with the outside atmosphere.

10. A liquid cooling system as defined in claim 9, in which said expansion tank is of a centrifuge structure adapted to deaerate the coolant circulating therethrough.

11. A liquid cooling system for internal combustion engines comprising a primary circulation line including the engine block, a radiator, a coolant pump, and a venturi before the intake to said pump; a centrifugal expansion tank connected to permit at least partial circulation of effluent engine block coolant; a static coolant reserve tank within said expansion tank and in heat exchange relationship with the coolant therein; a connection from said static tank to the throat of said venturi through which liquid head pressure of the static tank coolant is impressed on the system; a connection between said expansion tank and said static coolant reserve tank adapted readily to permit venting of air and vapor from the former to the latter tank and to resist similar flow of liquid, said connection including a valve operated by a float in said expansion tank; and pressure venting means on said static coolant reserve tank to control a vapor pressure preventing free boiling, while further preventing equalization of pressure with the outside atmosphere.
